UNITED STATES PATENT OFFICE.

GEORGE D. MORTON, OF KEY WEST, FLORIDA.

CRUDE-OIL BURNER.

1,172,032.

Specification of Letters Patent. Patented Feb. 15, 1916.

Application filed June 25, 1913. Serial No. 775,696.

To all whom it may concern:

Be it known that I, GEORGE D. MORTON, a citizen of the United States, residing at Key West, in the county of Monroe and State of Florida, have invented certain new and useful Improvements in Crude-Oil Burners, of which the following is a specification.

This invention relates to improvements in crude oil burners.

The primary object of this invention is the provision of a crude burner wherein the fuel, namely crude oil, is fed to the burner tip by means of gravitation and steam pressure; and one which is constructed so that the formation of carbon upon the interior of the burner will be practically eliminated, thus materially increasing the longevity of the burner and eliminating the necessity of cleaning the same at short intervals.

Another object of this invention is the provision of means for carrying away or disposing of the condensation of the steam, thus admitting only dry steam to the mixing chamber of the burner and materially increasing the combustibility of the oil.

A still further object of this invention is the provision of a crude oil burner in which the possibility of a back pressure of the steam upon the fuel inlet is entirely eliminated, thus allowing a constant flow of crude oil into the mixing chamber.

With the foregoing and other objects in view, this invention consists in such novel features of construction, combination and arrangement of parts as will be hereinafter more fully described, illustrated in the accompanying drawings and claimed.

In describing the invention in detail reference will be had to the accompanying drawing which shows the crude-oil burner proper in section.

In referring to the drawings by numeral, 1 designates a hollow metallic tube which has exterior screw-threads formed upon both ends thereof, as at 2 and 3. Mounted upon the upper end of the tube 1 and engaging the exterior screw-threads 2 is a burner tip 4 of the usual construction of burner tips employed for similar purposes having a flange 5, hexagonal in shape, formed upon its lower end to facilitate the removing of the burner tip from the upper end of the tube 1. The upper portion of the tip 4, which is rounded, as is clearly shown in the drawings, is provided with a slot 6 cut

therein which provides an outlet for the fuel which is forced into the tube 1 through the various inlets thereto.

The lower end of the tube 1 is seated in the flanged portion 7 of a T-connection 8, and is securely held therein by means of the external screw-threads 3 and internal screw-threads formed upon the interior of the flanged portion 7. The T-joint 8 is divided into separate compartments 9 and 10 by means of a partition 11 which extends diagonally across the interior of the T-joint 8, having a portion thereof which is substantially and centrally located within the T-joint 8 extending at right angles to the longitudinal lines of the tube 1, and provided with an aperture 12 extending therein. The aperture 12 has internal screw-threads formed thereupon which are engaged by external screw-threads formed upon the lower end of the tube or fuel pipe 14.

The tube or fuel pipe 14 passes upwardly into the tube 1; is centrally located therein and held rigidly in place by means of a web brace or support 15, which is formed on the interior of the tube 1 near the upper end of the feed pipe 14. The upper end of the feed pipe 14 is reduced, as at 16, so as to increase the force with which the fuel is emitted therefrom, and extends substantially into the tube 1 two-thirds of the length of the same. The container (not shown) which holds the supply of crude oil is preferably mounted at a higher elevation than that of the burner, so that the oil or fuel will be forced through the supply pipe to the compartment 9, and upwardly through the feed pipe 14 by the force of gravity.

The compartment 10 is connected to a steam inlet pipe 19, as at 20. The steam inlet pipe 19 has a valve 21 of the usual construction mounted therein for regulating the inflow of the steam, and also a goose neck or T-joint 22 connected thereto a short distance beyond the valve 21, as is shown at 23. The T-joint 22 communicates with the steam inlet pipe, and has a pipe 24 which is of a smaller diameter than the steam inlet pipe connected to the lower end thereof. The T-joint 22 is mounted in an upright position, and the steam pipe communicates with or is connected to the upper end of the same, while pipe 24 is connected to the T-joint 22 directly beneath the opening with which the steam pipe is connected. This mounting of the T-joint, the steam inlet

pipe, and the pipe 24 in the manner that has been heretofore described will provide a means for efficiently carrying off or disposing of the condensation of the steam, as 5 the water or condensation is heavier, and will consequently separate, the water falling downwardly into the pipe 24, and passing out of the same to the opening in the end 25 of the pipe 24. The pipe 24 has a 10 valve 26 mounted therein, so that, should it be desired, the outlet of the water may be cut off.

The steam entering the interior of the tube 1 through the compartment 10 will 15 pass upwardly therein, and intermingle with the fuel or crude oil which enters the upper portion of the tube 1 from the feed pipe 14, increasing the force with which the fuel is forced upwardly and out through the slot 20 6, as is well known in the construction of burners of this type. By extending the feed pipe 14 vertically into the tube 1 and causing the steam and the fuel to enter the tube 1, both moving in the same direction, the 25 mixing of the two will be greatly facilitated, and any back pressure of the steam upon the inlet of the fuel will be eliminated.

Copies of this patent may be obtained for five cents each, by addressing the "Commissioner of Patents,
Washington, D. C."

In practical fields, certain minor features of construction, combination and arrangement of parts may necessitate alterations 30 to which the patentee is entitled, provided such alterations are comprehended within the scope of what is claimed.

What is claimed is:

In an oil burner, the combination with a 35 T-joint divided into two compartments, a mixing chamber entering the joint and communicating with one of the compartments, an oil supply pipe entering the opposite compartment and extending longitudinally 40 of the mixing chamber and terminating intermediate the ends thereof, of a pipe leading from the compartment communicating with the mixing chamber, a T-shaped joint connected to said pipe, a fluid supply pipe 45 connected to the top of said joint, and an outlet pipe of less diameter connected to the opposite end of the T-shaped joint.

In testimony whereof I affix my signature in presence of two witnesses

GEORGE D. MORTON.
